SOUND MOTION PICTURE PROJECTOR

Elmar Maier, Vaduz-Muhleholz, Liechtenstein, assignor to
Carena S.A., Geneva, Switzerland

Filed Oct. 28, 1963, Ser. No. 77,204

Claims priority, application Switzerland June 5, 1963

Term of patent 14 years

(Cl. D61—1)

Fig. 1

Fig. 2

FIG. 1 is a side and rear perspective view of a sound motion picture projector showing my new design; and

FIG. 2 is a side and front perspective view thereof.

The bottom and the side of the projector not shown are conventional, plain and unadorned.

I claim:

The ornamental design for a sound motion picture projector, as shown and described.
